(57) **CLAIM**

The ornamental design for ultrasound therapy cap connection, as shown and described.

DESCRIPTION

FIG. 1 is a perspective view of a ultrasound therapy cap connection showing our new design, with a hand piece and corresponding connection structure of the hand piece shown in phantom;

FIG. 2 is a front elevational view thereof;

FIG. 3 is a rear elevational view;

FIG. 4 is a right side elevational view;

FIG. 5 is a left elevational view; and,

FIG. 6 is a top plan view thereof.

The broken line showing is for illustrative purposes only and forms no part of the claimed design.
